UNITED STATES PATENT OFFICE.

ADAM SCHEID, OF HARRISON, NEW JERSEY.

SHUTTLE-BOX-OPERATING MECHANISM FOR LOOMS.

SPECIFICATION forming part of Letters Patent No. 552,720, dated January 7, 1896.

Application filed August 27, 1895. Serial No. 560,659. (No model.)

To all whom it may concern:

Be it known that I, ADAM SCHEID, a citizen of the United States, residing at Harrison, Hudson county, and State of New Jersey, have 5 invented certain new and useful Improvements in Shuttle-Box-Operating Mechanism for Looms; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 The object of my present invention is to provide a shuttle-box-operating mechanism for looms in which the movements of the shuttle-box levers are controlled by a series of eccentrically - arranged cams operated 20 through cams on a wheel or disk secured on the main shaft.

The invention consists in the improved shuttle-box-operating mechanism, its lifting-levers controlling oscillating cam-wheels, in 25 the means for controlling the said cam-wheels, and in the combination and arrangements of the various parts thereof, substantially as will be hereinafter more fully described and finally embodied in the clauses of the claim.

30 Referring to the accompanying drawings, in which corresponding parts are indicated by like letters of reference in the several views, Figure 1 is a side elevation of a loom provided with my improvements, only those parts being shown which are necessary to illustrate the nature of my said invention; Fig. 2, an enlarged detail view of the upper shuttle-box lever-controlling cam-wheels and its operating mechanism; Fig. 3, a top plan view of Fig. 40 2; Figs. 4 and 5, left-hand end elevations of Fig. 2 in working and normal positions respectively; Figs. 6 and 7, views similar to Figs. 2 and 3, illustrating a modified form of the upper shuttle-box lever-operating and 45 controlling mechanism, and Fig. 8 an enlarged detail view in elevation of the pattern-chain and of the treadle-levers operated thereby.

In said drawings, *a* represents the frame of a loom; *c*, the shaft transmitting motion 50 through crank *c'* and pitman *c''* to the lay *f*, which latter is supported by sword *d*, ful-

crumed at its lower end, as at *e*, to the loom-frame.

The shuttle-boxes *f'*, which are arranged on each end of the lay *f*, are supported by the 55 rods *f''* and are guided by the blocks *f'''* secured to the lay-swords. On the shaft *c* is also secured the cam *c'* adapted to operate one arm of angle-lever *c''*, pivoted as at *c'''* to the frame, and controlled by spring *c''''*, all as 60 shown in Fig. 1 of the drawings. In a slot in the other arm of said angle-lever is arranged the pin *c'''* projecting from one end of link *c''''*, the other end of which is pivoted to the radial lever *c'''* carrying the pawl *c'''* adapted to 65 operate the ratchet-wheel *c'''*, secured to shaft *d''*, on which the said radial lever *c'''* is mounted, and which shaft has its bearings in the bracket-frame *c'''*. The projecting pin *c'''* of link *c''''* is adapted to be engaged by the hook 70 *c'''*, pivoted to the frame and operated through cord *c'''* from the Jacquard machine. All the above are of the well-known construction and as shown and described in the United States Letters Patent, No. 498,260. On the shaft *d''* 75 is also secured the sprocket-wheel *d'''* carrying the pattern-chain, adapted to control the treadles *d''''* *d'''*, which latter are connected by cords *d''''*, *d'''*, *d'''* and *d'''* respectively with the shuttle-box-operating mechanism, as will be 80 hereinafter more fully described.

In the frame *a* or in suitable brackets are secured the stub-shafts *b'*, *b''*, *b'''* and *b''''*, on each of which is arranged a sliding and oscillating cam-wheel *h''''*, *h'''*, *h''* and *h'* respectively. 85 Each of said cam-wheels is provided with an annular groove adapted to be engaged by a pin arranged on the free end of angle-lever *i''*, (or arm *i'''* for the right-hand cam-wheel, Fig. 2,) which angle-lever is loosely mounted 90 on the transverse shaft *i* having its bearings in the brackets *i'* *i''* projecting from the frame *a*. The other end of said angle-lever *i''* is connected through cord *d''* with its respective treadle *d''''*.

The arm *i'''*, controlling the cam-wheel *h'''* is secured to and operated by said shaft *i*, which latter is provided at its other end with an arm *i''*, connected by a cord *d'''* with its respective treadle *d''''*. Each of said cam-wheels *h''''*, *h'''*, *h''*, 100 *h'* is provided with an arm *h'*, from which projects a horizontally-arranged pin

h^2 , adapted to be engaged by the cams or projections g of the wheel or disk g^0 secured to the shaft b , which latter receives its motion from shaft c through a train of gears arranged 5 on the opposite end of the loom, of usual construction and not shown in the drawings.

On the outer periphery of each of the cam-wheels is arranged an eccentric projection h^3 , adapted at specified intervals during the operation of the machine to be brought into engagement with the lifting-lever f^6 and thus move the same upward.

A second and smaller cam projection h^4 is arranged alongside of eccentric projection h^3 , 15 as clearly shown in Figs. 1 to 5 inclusive, and which projection h^4 is adapted, when the lifting-lever f^6 is to be lowered, to be brought into engagement with the same and to thus support it during its downward movement, 20 the lever resting on the said projection h^4 which is returning with its carrying cam-wheel h^{20} to its normal position. A stop-pin a' for cam-wheel h^{20} (or a^2 for cam-wheel h^{21}) prevents the said cam-wheels from turning 25 beyond their normal and operative position, as will be manifest.

The spiral spring n' surrounding the stub-shaft is secured with one end to the cam-wheel and with its other end to the said stub-shaft or to a collar n fixed on the same.

Each of the levers f^6 and f^7 is provided on its under side with two lugs or stops f^{13} and f^{14} , adapted to be engaged by the pointed ends of the projections h^3 of their respective cam-wheels and to be thus held in raised position. The levers are provided about midway between said stops with a vertically-arranged slot f^{15} engaged by the pin f^{16} projecting horizontally from the frame a or a 35 suitable bracket thereof. The levers are controlled or held in engagement with the cams either by flat springs f^{11} or by spiral springs f^{12} . (See Fig. 1.)

The forward end of lever f^6 is pivotally 45 connected through link f^5 with the nut or collar f^4 on rod f^2 , while the forward end of lever f^7 operates through arm f^8 , the shaft f^9 traversing the loom and controlling through arm f^{10} the shuttle-box-supporting rod on the 50 other end of the machine.

In the modified form illustrated in Figs. 6 and 7 the cam-wheels h^{20} , h^{21} , &c., are each provided with an eccentric slot h^{10} , in which is adapted to operate the pin h^{11} projecting 55 horizontally from lever h^{12} . The said lever is provided at its lower portion with a vertical slot engaging the reduced outer portion of stub-shaft b' , while its upper end is pivotally connected, as at h^{13} , with the lifting-lever f^6 , 60 controlled by spiral spring f^{20} . A lateral motion of the lever h^{12} is prevented by the projections f^0 arranged on the lifting-lever f^6 and on each side of said lever h^{12} . In the present form a counterweight h^{13} is substituted for 65 the spiral spring n' of Figs. 2 to 5, inclusive.

It will be manifest that the pins h^2 can

each be provided with an antifriction-sleeve, if so desired.

The operation of the device is as follows, reference being made especially to Figs. 1, 2, 3, 4, 5, and 8. During the operation of plain weaving the shuttle-box-operating mechanism is at rest. The hook c^8 , having been lowered, engages the pin c^7 and thus prevents angle-lever c^4 from being operated by the cam c^3 on shaft c . When the jacquard calls for the introduction of a color to be worked in a fabric, the cord c^9 is drawn upward by the Jacquard mechanism, thus releasing the pin c^7 and thereby bringing the angle-lever c^4 into engagement with the cam c^3 . Through the link c^6 , radial lever c^{22} , and pawl c^{23} , the ratchet-wheel c^{24} is thus rotated the required distance. (In the drawings one-eighth of a revolution.) The shaft d^2 and sprocket-wheel d^3 are thus 80 revolved, operating the pattern-chain until one of its rollers comes under and lifts one of the levers d^4 d^5 . In Fig. 1 of the drawings is illustrated the position of lever f^6 when the first or top compartment of the shuttle-box 85 is brought opposite the lay or race and ready to discharge its shuttle. Supposing that the second shuttle from the top is called for after the first shuttle has performed its operation, the cam h^{20} remains in its raised position—that is to say, the angle-lever i^3 and its respective treadle d^4 are prevented from returning to their normal positions. The roller on the pattern-chain next to the roller which has lifted the said lever d^4 engages and travels 90 along the curved cam portion d^{20} of the latter and thus will keep the said treadle in its raised position. A second roller simultaneously lifts that treadle which controls through its cord connection the arm i^4 on shaft i , 95 which latter, through the arm i^5 , (its pin engaging the annular groove,) slides the cam-wheel h^{21} on the shaft b^2 until the pin h^2 is in the path of the cam projection g of wheel g^0 and the projection h^3 directly beneath the lever f^6 . The wheel g^0 in its rotation and through the projection g engaging the pin h^2 operates the cam-wheel h^{21} until the projection h^3 has raised the lever to its highest position. The pointed end of said projection now rests 100 against the lug or stop f^{14} , in which position it remains until the cam-wheel is about to be returned for a different shuttle-call, as will be manifest. Through the connection of the free end of lever f^6 with the shuttle-box- 105 supporting rod the latter is raised one compartment and thus the corresponding shuttle (the second one from the top) brought into operation. Should said shuttle be required for more than one pick, the hooked end lever 110 c^8 is lowered by the Jacquard machine into engagement with the pin c^7 of link c^6 , thus withdrawing the angle-lever c^4 from contact with cam c^3 , and thus preventing a further 115 rotation of the shuttle-changing device on shaft d^2 . Now supposing that the third shuttle from the top is required, it is necessary to

return the cam-wheels h^{20} and h^{21} to their normal position. The corresponding treadles d^4 and d^5 are lowered by the pattern-chain, thus releasing the angle-levers from the strain of the cord connections and thereby allowing the spiral springs n' to slide their respective cam-wheels h^{20} and h^{21} back on their stub-shafts until the pins h^2 are out of the path of the projections g of wheel g^0 , and the projections h^4 in alignment with the lever f^6 . The said lever will be forced downward upon said projections h^4 by the action of the springs f^{11} or f^{12} (see Fig. 1) and as the cam-wheels are oscillated backward and thus returned to their normal position by the action of the uncoiling of their respective spiral springs n' , the said lever f^6 will continue in its downward movement until it has reached its lowermost position. Through the connection of the free end of the lever f^6 with the shuttle-box-supporting rod said rod and the box are lowered one compartment and the second shuttle from the top is thus brought into operation. If the fourth shuttle from the top is called for the cam-wheel h^{21} is operated until the projection h^3 has raised the lever to its highest position, when the pointed end of said projection engages the lug or stop f^{14} , as will be manifest.

30 From the foregoing it can readily be seen that when the cam-wheels are operated to raise the lever they are brought into engagement with the same by their respective angle-levers and are oscillated by the projections g of wheel g^0 , while when the lever is to be lowered the spiral springs n' , which by the former operation has been depressed and coiled tighter, perform the operation of returning (oscillating backward) the said cam-wheels to their respective normal positions.

The mode of operation of the lower oscillating cam-wheels h^{22} and h^{23} and the connecting-lever f^7 is the same as that of the upper cam-wheel and its lever f^6 .

45 I do not intend to limit myself to the precise construction shown and described, as various alterations can be made without changing the scope of my invention; but

50 What I claim as new, and desire to secure by Letters Patent, is—

1. The combination with the shuttle box lifting lever, of a series of stub shafts, an oscillating cam wheel loosely mounted on each of said stub shafts, an eccentric projection on each of said cam wheels, said cam wheels and their respective eccentric projections being adapted to be oscillated on their respective shafts and thus be thrown into and out of engagement with said lever to operate the same, and means for oscillating said cam wheels, all said parts, substantially as and for the purposes described.

2. The combination with the shuttle box lifting lever, of a series of stub shafts, an oscillating cam wheel loosely mounted on each of said stub shafts, an eccentric projection on each of said oscillating cam wheels, a pin

projecting horizontally from each of said cam wheels, means for sliding said cam wheels and their respective projections into and out of engagement with said lever, and means to operate the pins to thus oscillate the cam wheels, all said parts, substantially as and for the purposes described.

3. The combination with the shuttle box lifting lever, of a series of stub shafts, an oscillating cam wheel loosely mounted on each of said stub shafts, a pin projecting horizontally from each of said cam wheels, means for sliding said cam wheels into and out of engagement with the lifting lever, means for operating the pins to thus oscillate the cam wheels, and means for holding the cam wheels in normal position, all said parts, substantially as and for the purposes described.

4. The combination with the shuttle box lifting lever, a series of stops or lugs on the under side of said lifting lever of a series of oscillating cam wheels, an eccentric projection on each of said cam wheels, and adapted to be thrown into and out of engagement with the said lifting lever and to engage the stops or lugs on the same, a pin projecting horizontally from each of said cam wheels, means for holding said cam wheels in normal position, and a wheel or disk provided with a series of projections adapted to engage and operate said pins to thus oscillate the cam wheels, all said parts, substantially as and for the purposes described.

5. The combination with the shuttle box lifting lever, of a series of stub shafts, an oscillating cam wheel loosely mounted on each of said stub shafts, an eccentric projection arranged on the periphery of each of said cam wheels, means for sliding said cam wheels and their respective projections into and out of engagement with the said lever, a pin horizontally projecting from each of said cam wheels, a wheel or disk provided with a series of cams or projections adapted to engage and operate the pins and to thus oscillate the cam wheels, means for turning said cam wheels backward—when released—into their respective normal positions, and springs for controlling the downward movement of the lifting lever, all said parts, substantially as and for the purposes described.

6. The combination with the revolving shaft (b), of a series of stub shafts, an oscillating cam wheel loosely mounted on each of said stub shafts and adapted to be intermittently operated by said revolving shaft, an eccentric projection on each of said cam wheels, the shuttle box lifting lever operated by two of said series of cam wheels, a series of stops or lugs on the under side of the lifting lever adapted to be engaged by the eccentric projections of its respective cam wheel and means for intermittently transmitting the motion of the revolving shaft to the said cam wheels, all said parts, substantially as and for the purposes described.

7. The combination with the revolving shaft

- (b), and with the shuttle box lifting lever, of a series of stops or lugs on the under side of the lifting lever, a series of oscillating cam wheels intermittently operated by said shaft, 5 an eccentric projection on each of said cam wheels and adapted to operate said lifting lever and to engage the said stops or lugs, means for intermittently transmitting the motion of the revolving shaft to said cam wheels, and 10 springs for controlling the downward movement of said lifting lever, all said parts, substantially as and for the purposes described.
8. The combination with the revolving shaft (b) and with the shuttle box lifting lever, of 15 a series of stops or lugs on the under side of the lifting lever, a wheel secured on said shaft and provided with a series of regularly arranged cam projections, a series of stub shafts arranged around and parallel with said shaft, 20 an oscillating cam wheel loosely mounted on each of said shafts, a series of eccentric projections on each of said cam wheels and adapted to be thrown into and out of engagement with the said lifting lever and its respective 25 stops or lugs, a pin projecting horizontally from each of said cam wheels and adapted to be engaged by the cam projections of the wheel on the revolving shaft, and means for throwing said cam wheels and their respective 30 pins into and out of engagement with said lifting lever and the cam projection carrying wheel respectively, all said parts, substantially as and for the purposes described.
9. The combination with the revolving shaft (b) and with the shuttle box lifting lever, of 35 a series of stops or lugs on the under side of the lifting lever, a wheel secured on said shaft and provided with a series of cam projections, a series of stub shafts parallel with said revolving shaft, a cam wheel loosely mounted on each of said stub shafts and provided with an eccentric projection, adapted to engage the lifting lever and its respective stop, a pin projecting horizontally from each of 40 said cam wheels, means for throwing said cam wheels with their respective eccentric projections and their horizontally arranged pins into and out of engagement with the lifting lever and the cam projection carrying 45 wheel respectively to thus operate the said lifting lever, and means for holding the said cam wheels in normal position, all said parts, substantially as and for the purposes described.
- 55 10. The combination with the continuously revolving shaft, of a series of stub shafts, a cam wheel loosely mounted on each of said stub shafts, means for intermittently transmitting the motion of the revolving shaft to 60 the said cam wheels, an eccentric projection

on each of said cam wheels, the shuttle box lifting lever, a series of stops or lugs arranged on the under side of the said lifting lever and adapted to be engaged by the said eccentric projections of the respective cam wheels, and 65 means for sliding said cam wheels and eccentric projections into and out of engagement with the said lifting lever and its stops, all said parts, substantially as and for the purposes described.

11. The combination with the continuously revolving shaft, of a wheel secured on said shaft and provided with a series of cam projections, a series of stub shafts around said revolving shaft, a cam wheel loosely mounted 75 on each of said stub shafts, an eccentric projection on each of said cam wheels, the shuttle box lifting lever, a lug or stop arranged on the under side of said lifting lever and adapted to be engaged by the eccentric projection, means for sliding said cam wheels and their respective projections into and out of engagement with the lifting lever and its stop or lug respectively, and a pin projecting horizontally from each of said cam wheels 85 and adapted to be operated by the said cam projections of the wheel on the revolving shaft, all said parts, substantially as and for the purposes described.

12. The combination with the pattern chain 90 and the treadle levers operated thereby, of a continuously revolving shaft, a wheel secured to said shaft and provided on its outer periphery with a series of cam projections, a series of stub shafts parallel with said revolving shaft, an oscillating cam wheel on each of said shafts and provided with an eccentric projection and with an annular groove, a pin projecting horizontally from each of said cam wheels, a lever adapted to engage the annular groove of its respective cam wheel and operated through a cord or wire connected with its respective treadle lever, the shuttle box lifting lever operated by two of said series of cam wheels, a series of stops or lugs 95 on the under side of the lifting lever and adapted to be engaged by the eccentric projection of its respective cam wheel, means for controlling the return motion of said shuttle box lifting lever, and means for holding the 100 cam wheels in normal position, all said parts, substantially as and for the purposes described.

In testimony that I claim the foregoing I have hereunto set my hand this 7th day of 115 August, 1895.

ADAM SCHEID.
